UNITED STATES PATENT OFFICE.

ORRIE H. FISBURNE, OF BROOKLYN, NEW YORK.

SWING.

Application filed May 9, 1922. Serial No. 559,509.

To all whom it may concern:

Be it known that I, ORRIE H. FISBURNE, a citizen of the United States, and a resident of the city of New York, borough of Brooklyn, in the county of Kings and State of New York, have invented a new and Improved Swing, of which the following is a full, clear, and exact description.

This invention relates to lawn swings and has particular reference to lawn swings of the oscillatory type.

As an object the invention contemplates in a lawn swing of the character described a swing body, a base, and means for mounting and supporting said swing body upon the base to cause said body to move in an arcuate path upon reciprocations of the same whereby to simulate a swinging action.

As a further object the invention contemplates in a lawn swing of the character set forth, means operable by the occupants of the swing for effecting reciprocations of the same.

Furthermore the invention contemplates a lawn swing which is extremely simple in its construction, inexpensive to manufacture and which is highly amusing and attractive in its use and operation.

With the above recited and other objects in view, the invention resides in the novel construction set forth in the following specification, particularly pointed out in the appended claims and illustrated in the accompanying drawings, it being understood that the right is reserved to embodiments other than those actually illustrated herein to the full extent indicated by the general meaning of the terms in which the claims are expressed.

10 In the drawings—

Figure 1 is a perspective view of a lawn swing constructed in accordance with the invention.

Fig. 2 is a longitudinal sectional view therethrough illustrating the swing body in its normal intermediate position.

Fig. 3 is a similar view illustrating the swing body in its oscillated position with respect to the supporting base.

Fig. 4 is a transverse sectional view taken approximately on the line 4—4 of Fig. 2.

Fig. 5 is a similar view taken approximately on the line 5—5 of Fig. 2.

Fig. 6 is a horizontal sectional view through the top, taken approximately on the line 6—6 of Fig. 2.

Referring to the drawings by characters of reference, the swing comprises a base A, a swing body or car B mounted on said base for oscillatory movement, and a top C detachably associated with and carried by the swing body or car B. The base A consists of a rectangular frame including side rails 10, end rails 11, and intermediate cross rails 12 spaced from the opposite ends of the frame. A pair of arcuate tracks 13 are supported longitudinally within the frame A with one track of each pair arranged in parallel spaced relation to the side rails 10 and disposed between the end and intermediate rails 11 and 12. Preferably the tracks 13 are supported from blocks 14 secured to the side rails and interposed in the entrant angle formed at the juncture of the end and intermediate rails with the side rails. Suitable angular braces or trusses 15 connect the end rails with the side rails at the corners thereof for the purpose of strengthening the structure of the base. The swing body or car B embodies a rectangular frame consisting of side rails 16 and end rails 17 upon which longitudinally spaced transversely disposed seats 18 are arranged facing one another. Longitudinally spaced pairs of arcuate tracks 19 are supported by blocks 20 attached to the side rails 16 and the individual tracks of each pair are spaced from the side rails in parallel relation thereto. The means for supporting the car or swing body B from the base for oscillatory movement consists of a truck or platform D which includes parallel transversely spaced longitudinal stringers 21 from the opposite extremities of which bearing arms 22 depend and within the lower free extremities of which bearing arms, transverse shafts 23 are mounted. A pair of peripherally grooved rollers or wheels 24 are carried by the shafts 23 and are adapted to be interposed between the tracks 13 and 19 of the base and car or swing body. The transverse roller shafts 23 are connected to each other by longitudinal reach bars 25 and the stringers 21 are connected by transverse slats 26 which also constitute a floor for the car or swing body which is subterposed with respect to the seats 18.

The side rails 16 are connected by intermediate transverse brace rods 27 which in addition to bracing the frame of the car or swing body coact with the stringers 21 to prevent disassociation of the truck or plat-

form D from the car or swing body and serve as a means for lifting the truck with the car or swing body when the same is lifted from the base, without permitting of the retraction of the tracks 19 from the grooves in the platform wheels 24. The brace rods 27 further coact with the under side of the stringers 21 to limit the oscillatory movement of the car body B and truck 10 or platform D with respect to each other and with respect to the base A. Preferably the side and end rails 16 and 17 of the frame of the car or swing body are braced by angular corner braces or trusses 28 which 15 braces are connected respectively at their opposite extremities to the side and end rails thereof. The arcuate track rails 13 and 19 are arranged with their convex faces in opposed relation whereby relative longitudinal movement of the car or swing body B with respect to the base A will effect the climbing of the rollers or wheels 24 to the upper or elevated portion of the lower tracks 13, while the opposite lower portions of the 20 tracks 19 will climb the rollers or wheels 24 to elevate the entire car or swing body B with respect to the base A. It is of course obvious that the truck D in its entirety moves in an oscillatory path with the car or 25 swing body B, but it will be observed that said truck moves at approximately one-half the rate of speed of the car or swing body and approximately one-half of the distance of said car or swing body. Normally the 30 truck D and the car or swing body B are disposed in an intermediate position with the upper and lower peripheral edges of the rollers or wheels 24 in engagement with the lowermost portion of the lower tracks 13 and 35 the uppermost portion of the upper tracks 19, said position being assumed due to gravity. The movement of the swing body is accomplished manually by the occupants of the seats by pushing the feet against the 40 slats 26 of the truck, while seated on the seats 18, which results in relative longitudinal movement of the car body B with respect to the truck. After the car or swing body is initially set in motion, the operation 45 due to momentum effects the partial climbing of the rollers from one elevated end of the lower tracks 13 to the opposite elevated ends thereof.

The top or cover C comprises a strip of 50 canvas or other suitable material 30 of rectangular formation having depending side flaps or curtains 31 which is detachably supported from the car body B by means of the inverted U-shaped supporting bails 32, the 55 connecting bights 33 of which are arranged transversely within the opposite ends of the top and the free extremities of the side legs, which are received by bearing eyes 60 at the corners of the frame of the car 65 B. The top or cover C is maintained in

distended condition through the medium of cross slats 35 which extend diagonally of the strip 30 and which are notched at their opposite extremities as at 36 to coact and engage with the bights 33 of the bails 70 for the purpose of holding the bails in place.

If desired a table 38 is adapted to be associated with the car or swing body B in transverse position between the seats 18. 75 The table is associated with the swing body by inserting the lower extremities of the pivoted legs 39 in apertures 40 in the side rails 16. When not in use the legs 39 are adapted to be folded upwardly and under 80 the table to lie parallel with the bottom thereof.

I claim:

1. A swing embodying a base, a swing body, means for supporting said body from 85 the base for oscillatory movement with respect thereto, a connection between said means and the swing body constituting means for limiting the oscillations of the swing, and means for lifting the supporting 90 means from the base with the swing body.

2. A swing including a base having upwardly curved arcuate tracks, a platform having wheels supported on said tracks for longitudinal oscillatory movement, a swing 95 body having downwardly curved arcuate tracks coacting with said platform wheels for supporting the swing body therefrom for independent relative movement with and in the same direction as the platform at a 100 higher rate of speed, and means on the car body adapted to coact with the platform for limiting the oscillation of the platform with respect to the car body and of the car body with respect to the base. 105

3. A swing including a base having upwardly curved arcuate tracks, a platform having wheels supported on said tracks for longitudinal oscillatory movement, a swing body having downwardly curved arcuate 110 tracks coacting with said platform wheels for supporting the swing body therefrom for independent relative movement with and in the same direction as the platform at a higher rate of speed, and means on the car 115 body adapted to coact with the platform for limiting the oscillation of the platform with respect to the car body and of the car body with respect to the base, said means also serving as a means for lifting the platform 120 with the car body from the base.

4. A swing including a base having upwardly curved arcuate tracks, a platform having peripherally grooved supporting wheels engaging said tracks for mounting 125 the platform from the base for longitudinal oscillatory movement, a swing body having downwardly curved arcuate tracks mounted on said platform, wheels for supporting the swing body therefrom for independent rela- 130

tive oscillatory movement with respect to and in the same direction as the platform and at a higher rate of speed, and transverse brace bars on said swing body disposed beneath the platform and adapted to coat therewith to constitute means for limiting the oscillation of the platform with respect to the base and

the car body with respect to the platform, said bars also constituting means for lifting the platform with the car body from the base without permitting the retraction of the arcuate tracks of the body from the peripheral grooves of the platform wheels.

ORRIE H. FISHBURNE.
